UNITED STATES PATENT OFFICE.

GEORGE H. BROWN, OF PORTLAND, OREGON.

DRAG SAW.

Application filed January 8, 1921. Serial No. 435,902.

To all whom it may concern:

Be it known that I, GEORGE H. BROWN, a citizen of the United States, residing at Portland, in the county of Multnomah and State of Oregon, have invented a new and useful Drag Saw, of which the following is a specification.

This invention relates to sawing machines, and more particularly to sawing machines of the drag saw type.

The primary object of the invention is to provide a novel form of sawing machine, wherein the saw and saw carriage move with respect to the log or material under operation, thereby eliminating the necessity of providing complicated mechanism for handling heavy logs.

A further object of the invention is to provide a machine of this character wherein the saw carriage support may be adjusted vertically with respect to the log or work, to enable logs of various diameters to be sawed.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:—

Figure 1 illustrates a side elevational view of a sawing machine constructed in accordance with the present invention.

Figure 2 illustrates a plan view of the same.

Figure 3 illustrates a sectional view taken on line 3—3 of Figure 2.

Figure 4 illustrates a sectional view taken on line 4—4 of Figure 2.

Referring to the drawings in detail, the sawing machine includes an upper section which is adjustably supported with respect to the bases 5 which are secured against movement, and which support the upper section or frame of the machine.

The frame of the machine is formed of the side rail supports 6 to which are secured the leg sections 7 adjustably connected to the

leg sections 8 as by means of the clamp or clamping collar 9, so that the frame is vertically adjustable.

Supported intermediate the ends of the frame, are the standards 9', which have the lower portions thereof connected to the base blocks 10, the lower portion of the standards 60 being cut away to provide guideways 11 for the adjustable clamping member 12 which clamping member is provided with a longitudinal bore to accommodate the threaded rod 13, there being provided an operating 65 handle 14 on one end of the rod, whereby the rod may be rotated to move the log clamping member transversely of the machine.

The clamping member also includes a vertical arm 15 in which operates the hook 16 which is pointed to pierce the log to prevent movement thereof. At the rear of the hook 16 is formed a plurality of teeth 17 which cooperate with the teeth 18 formed on one 75 end of the handle 19 that operates to move the hook 16 vertically to grasp logs of various diameters.

Supported by the standard 9' is a suitable trackway which comprises side rails 6 and 80 carrying tracks 20 and 21 on which tracks moves the carriage 22 which supports the engine 23 and drag saw 24, the saw being operated by the engine.

The drag saw reciprocates on the rods 25 85 in a well known manner, the rods being supported by means of the supporting rod 26 which has connection with the carriage 22, the connection between the rod 26 and rods 25 being such as to permit of reciprocating 90 motion of the drag saw, but restrict swinging motion thereof.

Forming a part of the engine is a fly wheel 27 that is supported on one end of the shaft 28 which carries a sprocket wheel 29, 95 the sprocket wheel 29 being designed to impart rotary motion to the sprocket wheel 30 through the medium of the chain 31, there being provided a crank arm 32 operated by the sprocket for imparting reciprocating motion to the drag saw 24.

The shaft 33 supports the sprocket wheel 30 and this shaft also supports the worm 34, which meshes with the gear 35 that transmits rotary motion to the friction pulley 36, 105 which contacts with the disk face of the gear

35, and imparts rotary motion to the shaft 37 to which the pulley 36 is keyed.

On one end of the shaft 37 is supported a drum 38, which revolves with the shaft and 5 accommodates the flexible member 39, one end of the flexible member being anchored to the frame as at 40 so that when the drum revolves to wind the flexible member 39, the carriage will be moved towards one end of 10 the frame to feed the saw through the log being sawed.

In order that the drum 38 may be revolved at various speeds, a handle 41 is provided, which handle moves the friction pulley 36 to 15 various locations with respect to the wheel 35 to cause the pulley 36 to engage the wheel 35 at various locations on its side face. Thus it will be seen that by adjusting the speed of the drum, the travel of the carriage may 20 be regulated according to the stroke of the saw.

The rails 6 carrying tracks 20 21 are supported on the vertically adjustable horizontal bars 42, which have lateral extensions 25 43 and 44, formed on the depending portion 45 to set up a binding action between the bars 42 and their supporting standards 9'. Formed in the depending portion 45 is an 30 opening designed to accommodate the bolt 46 which also passes through one of the openings 47 formed in the standards 9 to permit 42 and their supporting standards 9. the bars 42 to be held in various positions of adjustment.

35 It might be further stated that the level

11' is provided on the guideway 11 so that the machine may be properly positioned.

Having thus described the invention, what is claimed as new is:—

1. In a sawing machine, a base including 40 spaced members, guide ways supported on the spaced members, adjustable clamping members movable in the guide ways means for adjusting the clamping members longitudinally of the guide ways, a vertically adjustable track section disposed above the clamping members, a carriage on the track section and adapted to travel thereon transversely of the guide ways, and a saw mounted 45 on the carriage.

2. In a sawing machine, a base comprising 50 spaced members formed with guide ways, standards supported by the base, horizontal bars supported by the standard and adjustable vertically with respect thereto, a track section supported by the horizontal bars and disposed above the guide ways, a saw supporting carriage traveling on said track section at right angles with respect to the guide ways, and log clamping means disposed under the track section, and adjustable in said guideways.

In testimony that I claim the foregoing as my own, I have hereto affixed my signature in the presence of two witnesses.

GEORGE H. BROWN.
